UNITED STATES PATENT OFFICE.

FRANKLIN L. LANE, OF BELOIT, WISCONSIN, ASSIGNOR TO P. B. YATES MACHINE COMPANY, OF BELOIT, WISCONSIN, A CORPORATION OF WISCONSIN.

LUBRICATING SYSTEM.

1,200,626.

Specification of Letters Patent.

Patented Oct. 10, 1916.

Application filed September 20, 1915. Serial No. 51,539.

To all whom it may concern:

Be it known that I, FRANKLIN L. LANE, a citizen of the United States, residing at Beloit, in the county of Rock and State of Wisconsin, have invented certain new and useful Improvements in Lubricating Systems, of which the following is a specification.

The invention has for its principal object the provision of simple and efficient means for lubricating shafts and particularly those vertically disposed and including a foot-step bearing, as for instance the side-head spindle of wood working machines in which latter connection the invention is herein illustrated although by no means limited to such application. By reason of the fact that the invention is capable of embodiment in varied constructional forms and in different relations the accompanying drawing and detailed description based thereon are to be taken in an illustrative and not in an unnecessarily limiting sense.

In the drawing—Figure 1 is a vertical section through shaft bearings illustrating the invention; and Figs. 2 and 3 are horizontal sections on the lines 2—2 and 3—3 respectively.

In the embodiment chosen for purposes of illustration the machine frame 11 has fulcrumed in its lower portion at 12 a lever 13 the opposite end of the lever arm having threaded engagement at 14 with a screw spindle 15 loosely traversing the bracket 16 rigidly attached to the machine frame. The screw spindle is encircled by the spring 17 disposed between the lever 13 and the bracket 16 and bearing downwardly upon one and upwardly upon the other. A nut 18 engages the spindle above the bracket 16 and is frictionally held by the spring detent 19. By the lever 13 between its fulcrum 12 and its connection at 14 with the screw spindle is supported an oil well casing or box 20 provided with a sight gage 21 and a T-connection 22 through which latter the oil may be drained from the casing when desired. A cover for the casing is represented at 23 which is removable for the purpose of replenishing the oil well within the casing. An inner wall 20^a forming the false bottom of the oil well has a central recess 24 within which is seated the stud 25 on the lower face of a foot step block 26 having an upper flat face, the block being retained between the side walls of an upper larger recess 27.

The recess 27 and the block 26 are shown as of substantially circular cross section with the exception that on one side the block and recess are provided with co-operating projecting portions 26^a and 27^a in order to bring about a relative engagement to prevent rotation of the block while permitting the same to rock freely within the recesses 24 and 27. The supporting wall 20^a and the foot-step block 26 have central bores 28 and 29 respectively which are in register with each other in order to afford a channel through said wall and block for the oil.

Seated at its lower end upon block 26 is the vertical shaft or spindle 30 having a short distance above its lower end an annular recess 31 for the reception of a sectional washer 32 which may be of the same metal as the foot-step block 26 and preferably brass. This washer 32 is contained within the lower end of a threaded sleeve 33 and bears upwardly against a flange 33^a of said sleeve. The sleeve 33 is screw threaded within the upper portion of the oil well casing and serves to confine the shaft to a limited vertical movement by means of the engagement of the washer 32 within the annular recess 31.

It will be observed that the position of the shaft is vertically adjustable by means of the screw spindle 15 acting upon the free end of the lever 13 and that vertical vibration of the shaft is absorbed by the spring 17 acting upon the lever 13 and the bracket 16 of the machine frame.

Within the machine frame is mounted above the oil well casing a box 34 providing a journal bearing for the shaft, the babbitted portion 35 of the bearing having on one side a longitudinal groove 36 closed below and upon the opposite side a longitudinal groove 37 open below at a point above the oil well. Communication is established between the grooves 36 and 37 at the upper end of the journal bearing by an annular groove 38, it being noted in passing that the groove 37 has a cross sectional area substantially twice that of the groove 36 for a purpose which will hereafter be made apparent. The lower end of the shaft is provided with a bore 39 which coincides with the axis of the shaft at the lower terminus thereof and thence extends upwardly at an angle to the axis of the shaft and at 40 has a port opening to the shaft periphery at a

point adjacent the level of the closed lower end of the groove 36.

It will be observed that the oil within the well will rise within the bore 39 through the bores 28 and 29 and as the shaft rotates the oil will be fed upwardly by centrifugal action through the bore 33 and its outlet 40 into the groove 36 and also to the groove 37 as the port registers alternately with said 10 grooves. The oil introduced to the groove 40 is forced by the incoming oil upwardly to the annular groove 38 and thence passes through the groove 37 whence it flows downwardly through the open lower end of the 15 groove 37 and discharges into the oil well.

Above the journal bearing 34 and beyond the drive pulley 41 is arranged another journal bearing 42 the babbitt portion 43 of which has at one side a longitudinal groove 20 44 for the accommodation of the lubricating member 45 here represented as a wick the outer end of which dips within a body of oil 46 the oil being conveyed upon the rotation of the shaft by said wick from the oil well 25 and serving to lubricate the upper portion of the shaft.

The alinement of the shaft and its journal box is provided for by means of a plurality of screws, herein shown as three in number, 30 engaging the machine frame and journal bearings, certain of the screws arranged to force the journal bearing in one direction and certain others to force it in the opposite direction whereby the same may be adjusted 35 and firmly positioned. These screws are advantageously arranged in line longitudinally of the shaft and referring to the upper bearing 42 the screws 47 are threaded in the machine frame and bear inwardly 40 against the journal box 42 while the intermediate screw 48 is threaded in the journal box and bears upon the frame. In the lower journal bearing 34 the conditions are reversed without change of function, the 45 upper and lower screws 49 having threaded engagement with the journal box while the screw 50 has threaded engagement with the machine frame and bears inwardly upon the journal box.

50 I claim:

1. The combination with a rotatable shaft, and a journal bearing therefor, of an oil well within which a portion of the shaft is submerged, the submerged portion of the shaft having a bore with an inlet exposed to the oil and extending at an angle to the shaft axis and discharging to the shaft periphery within the journal bearing.

60 2. The combination with a rotatable shaft, and a journal bearing therefor, of an oil well within which a portion of the shaft is submerged, the submerged portion of the shaft having a bore with an inlet exposed to the oil and extending at an angle to the shaft axis and discharging to the shaft pe-

riphery within the journal bearing, the bearing having on one side thereof a longitudinal groove closed at one end and at the opposite side a longitudinal groove open at that end, and an annular groove connecting the two longitudinal grooves whereby the oil will flow by centrifugal action from the oil well along one side of the bearing and return along the other side to the well.

3. The combination with a rotatable shaft 75 disposed at an angle to the horizontal, and a journal bearing therefor, of an oil well within which the lower end of the shaft is submerged, the submerged end of the shaft having a bore with an inlet exposed to the 80 oil and extending at an angle to the shaft axis and discharging to the shaft periphery within the journal bearings at the lower end thereof, the bearing having on one side thereof a longitudinal groove closed at the 85 lower end and at the opposite side a longitudinal groove open at the lower end and at the upper end an annular groove connecting the two longitudinal grooves, whereby the oil will flow by centrifugal action from the 90 oil well up one side of the bearing and return down the other to the well.

4. The combination with a vertically disposed rotatable shaft and a journal bearing therefor, of an oil well within which the 95 lower end of the shaft is submerged, the submerged end of the shaft having an axial bore with an inlet exposed to the oil and extending at an angle to the shaft axis discharging to the shaft periphery within the 100 journal bearings at the lower end thereof, the bearing having at one side thereof a longitudinal groove closed at the lower end and at the opposite side a longitudinal groove of greater cross section open at the 105 lower end above the oil well, the journal bearing provided with an annular groove connecting the upper ends of the two longitudinal grooves, whereby the oil will flow by centrifugal action from the oil well up 110 one side of the bearing and return along the other to the well.

5. In a lubricating system, a machine frame, an oil well casing supported thereby for vertical adjustment on the latter, a foot-step block having an upper flat surface rockingly supported in the casing, means to prevent rotation of the block, and a vertical shaft suitably journaled and resting with its lower end on the block, the block adapted to be submerged in the body of oil in the well, the block having an axial bore and the shaft having a bore registering with the bore in the block and extending at an angle to the shaft axis and discharging to the 115 shaft periphery within the journal bearing, the bearing having on one side thereof a longitudinal groove closed at the lower end and on the opposite side a longitudinal groove open at the lower end, the journal 120

bearing provided with an annular groove connecting the upper ends of the two longitudinal grooves, whereby the oil will flow by centrifugal action from the oil well 5 through the foot-step block and the bore of the shaft up along one side of the bearing and return along the other side to the well.

6. In a lubricating system, a machine frame, an oil well casing supported thereby 10 for vertical adjustment on the latter, a foot-step block having an upper flat surface and rockingly supported in the casing by means of a lower stud carried by the block and seated in a recess in the bottom of the cas- 15 ing; means to prevent rotation of the block, a vertical shaft suitably journaled and resting with its lower end on the block, the block adapted to be submerged in the body of oil in the well, the block having an axial 20 bore and the shaft having a bore register-

ing with the bore in the block and extending at an angle to the shaft axis and discharging to the shaft periphery within the journal bearing, the bearing having on one side thereof a longitudinal groove closed at 25 the lower end and on the opposite side a longitudinal groove open at the lower end, the journal bearing provided with an annular groove connecting the upper ends of the two longitudinal grooves, whereby the 30 oil will flow by centrifugal action from the oil well through the foot-step block and the bore of the shaft up along one side of the bearing and return along the other side to the well.
